[57] ABSTRACT

In first and second forms of variable-delivery reciprocating pumps wherein fluid delivery past a first spring-

loaded delivery check valve is provided, delivery per stroke is decreased with increasing pump drive speed by provision of a second spring-loaded check valve having a smaller inertia-to-spring force ratio than that of the delivery check valve, so that the second check valve is temporarily opened by peak pressures occurring in the cylinder to release fluid from the pump cylinder. Delivery is basically controlled in the first pump by controlling the point during the stroke when the piston closes off an inlet port, and in the second pump by controlling the point when the cylinder is connected to a spill-back conduit, and in either pump the basic control also may vary the spring loading on the second check valve. Variation of the spring loading on the second check valve allows one to render the characteristic of the first pump more or less dependent upon the delivery control setting. In a preferred third variable-delivery reciprocating pump, delivery is initiated by closing an inlet port and opening an outlet port with an overlap during which a finite minimum port area for fluid flow from the pump cylinder causes a finite maximum restriction to flow from the cylinder and a peak pressure within the cylinder. A spring-loaded check valve responsive to cylinder pressure diverts fluid from the cylinder. Delivery is basically controlled by adjusting the points during the stroke at which the inlet port is closed and the outlet port opened. By suitably arranging the port geometry, the finite minimum port area occurring during the stroke may be made to automatically vary with the basic delivery adjustment in accordance with a desired relationship.

PUMP APPARATUS

This application is a division of my prior copending Application Ser. No. 155,114 filed June 21, 1971 now U.S. Pat. No. 3,739,809, which in turn is a division of my prior Application Ser. No. 857,162 filed Sept. 11, 1969, now U.S. Pat. No. 3,614,944, issued Oct. 26, 1971, and a continuation-in-part of my prior applications Ser. No. 786,233 filed Dec. 23, 1968, now abandoned, and Ser. No. 153,460 filed June 1, 1971 now Pat. No. 3,740,172.

It is desirable, after starting, and during normal "warmed up" operations, that the fuel-to-air ratio of the mixture burned by an engine either remain relatively constant or vary slightly in a desired sense over a wide range of speed and load conditions. It is generally preferred that the ratio either remain constant or vary slightly inversely with engine speed. Most internal combustion engines are controlled by a "primary control" which operates basically to control engine torque. In most carburetor-equipped engines the engine primary control controls torque by adjusting a throttle plate to adjust the amount of fuel-air mixture aspirated into an engine cylinder during a stroke. The amount of mixture aspirated per stroke determines the amount of air drawn into the carburetor air intake per stroke, and because of the venturi principle upon which the carburetor operates, the amount of fuel mixed with air varies rather proportionally. Because carburetor air flow inherently controls carburetor fuel flow, the fuel-to-air ratio of the mixture inherently tends to remain somewhat constant over a wide range of engine speeds. Any unwanted variation can be corrected easily in a number of ways, such as by use of a metering needle valve moved in response to engine vacuum.

While fuel injection engine systems have a number of advantages over carburetor-equipped engine systems for a number of applications, fuel injection systems do not have the above-described automatic mixture-maintaining tendency of carburetor systems. In fuel injection systems engine torque is usually controlled by simultaneous variation of the amount of fuel pumped per stroke and the amount of air aspirated per stroke, with the engine torque control linked to both vary the amount of fuel pumped per stroke and to vary a throttle plate in the air intake duct. When a decrease in engine load causes an increase in engine speed at a given torque control setting, the increased air flow causes an increased pressure drop across the air intake structure, decreasing the amount of air aspirated per stroke. With the amount of air aspirated per stroke decreased and the amount of fuel pumped per stroke remaining the same, it will be seen that the fuel-to-air ratio disadvantageously tends to increase as engine speed increases due to decreased load at a given torque control setting. While such a variation to fuel-air ratio is not regarded as a serious limitation in many applications, in certain other applications, and particularly in those where the engine frequently operates under widely-varying load conditions, it is desirable that fuel delivery vary inversely with engine speed, or directly with engine load, as well as with adjustment of the engine torque control, or "primary control." The variation of fuel delivery so as to maintain a desired fuel-to-air relationship may be termed "secondary control." It is a principal object of the invention to provide improved pump apparatus having effective and reliable means which provide

5
pump operating characteristics such as those useful for automatic secondary control.

Secondary control, or automatic variation of fuel delivery with engine speed in order to keep the fuel-air mixture relatively constant, is known in the prior art in connection with diesel engines and certain gasoline engines which use fuel injection. One prior art system is shown in U.S. Pat. No. 3,443,554, for example. However, those prior art systems of which I am aware require a centrifugal governor and/or other very complex and expensive mechanisms in order to provide such pump delivery versus speed characteristics. A very important object of the invention is to provide such pump characteristics in a reciprocating pump using much simpler and more economical apparatus which is easily constructed and highly reliable. Use of the present invention allows one to replace extremely complex and expensive mechanisms with merely a spring-loaded check valve.

In some prior art pumps used in fuel injection systems, the maximum pressures developed in the injection pump during an engine cycle vary appreciably with both engine speed and the fuel delivery setting of the basic torque control, while the maximum pressure developed in various other systems varies substantially solely with engine speed and is substantially independent of the fuel delivery setting of the basic torque control. As will be seen below, desired automatic control of some reciprocating pump systems may be obtained solely by use of a spring-loaded check valve having a constant spring load, and desired automatic control of the other prior systems may be obtained very simply by use of a spring-loaded check valve together with means for varying the spring load as a function of the setting of the basic torque control. Thus further objects of the invention are to provide improved reciprocating pumps of both types having desired delivery versus speed characteristics.

Several basically-different types of variable-delivery reciprocating pumps are known, and used in fuel injection systems, for example, and another object of the invention is to provide delivery versus pump speed control arrangements which are useful with each of the different types of pumps.

A principal object of the present invention is to provide an automatic desired variation of pump delivery with pump drive speed.

Other objects of the invention will in part be obvious and will in part appear hereinafter.

The invention accordingly comprises the features of construction, combination of elements, and arrangement of parts, which will be exemplified in the constructions hereinafter set forth, and the scope of the invention will be indicated in the claims.

For a fuller understanding of the nature and objects of the invention reference should be had to the following detailed description taken in connection with the accompanying drawings, in which:

FIG. 1 is a cross-section view of a reciprocating variable-delivery pump of the type shown in my prior application Ser. No. 786,233 modified to incorporate a secondary control delivery versus speed characteristic in accordance with the present invention.

FIG. 1a shows a modification to the pump of FIG. 1 to provide a different type of oil pumping.

FIG. 1b is a porting diagram useful in understanding the operation of the pump of FIG. 1.

FIGS. 2a, 2b and 2c are diagrammatic views useful in explaining the operation of the invention with each of three different types of reciprocating, variable-delivery, constant stroke-length fuel injection pumps.

FIG. 2a diagrammatically illustrates the application of the invention to a well-known form of fuel injection system using a variable-delivery reciprocating pump in which delivery is varied by varying the time or point during the stroke at which an inlet port is closed off. The engine crankshaft is mechanically connected to reciprocate piston P a fixed stroke distances within cylinder CY. Piston P is provided with an axial length which varies angularly around the piston, so that rotating piston P to various angular positions will vary the time or position during each stroke at which the piston covers inlet port IP. If port IP is closed off early during the stroke, greater delivery will result. During a rightward pumping stroke, fuel will be expelled through inlet port IP back to the supply tank until the piston blocks the port, and forward pumping will occur through delivery check valve DV to nozzle NO after the piston blocks the port until the end of the stroke. The angular position of piston P is controlled by the engine primary control, which is shown as comprising an accelerator pedal A. The primary control also varies air intake throttle plate TP via a cam or suitable linkage L to generally increase air flow as fuel quantity is increased. At a given setting of the primary control, an increase in engine speed due to a decrease in load will decrease the amount of air aspirated per stroke due to the restriction of the air intake structure S, thereby undesirably increasing the fuel-air mixture ratio.

As piston P of the injection pump travels rightwardly on a pumping stroke from the leftward limit position shown in FIG. 2a, fluid will initially be expelled out inlet port IP. If piston velocity were uniform, the pressure within the cylinder during the initial travel would tend to be a constant value dependent upon piston speed and the restriction of unblocked port IP. If piston P is instead reciprocated with simple harmonic motion, or an approximation or modification thereof, as is usually the case in practical systems using cranks or eccentrics or the like, the linear velocity of the piston will instead vary approximately cosinusoidally, for example, from zero velocity at the leftward position shown to a maximum speed at mid-stroke, down to zero velocity at the end of the rightward stroke. The linear velocity, assuming simple harmonic motion, may be written as (taking mid-stroke as the origin):

$$v = s/2\omega \cos \omega t \quad (1)$$

With piston velocity increasing during the initial portion of the stroke, the flow Q through port IP will similarly increase in direct proportion. From Torricelli's theorem ($p = Q^2/A^2$) it is evident that the pressure drop across the port, and hence the pressure within the cylinder, will vary as the square of the flow Q, and vary inversely with the square of the area of the port, and hence the pressure will increase approximately in accordance with an $\omega^2(\cos \omega t)^2$ characteristic, where ω is pump drive speed in radians per second. Thus the pressure existing in the cylinder when the piston edge reaches the inlet port will be higher at higher pump drive speeds, varying approximately with the square of pump drive speed. If the area A of port IP is large,

the pressure built up in the cylinder prior to closure of the inlet port will still be very modest, however, and in many systems is small enough to be neglected.

If at a given pump drive speed the piston is rotated to close off port IP later during the stroke, so as to provide lesser delivery per stroke, but still prior to mid-stroke, the piston will be seen to reach a greater linear velocity by the time it begins to close off port IP, and hence a greater pressure will exist when closure begins than at greater delivery settings. At any given pump drive speed, the maximum pressure would be developed if port IP is closed off approximately at midstroke, when the piston is at its maximum linear velocity. If piston P is rotated to provide port closure very late during the stroke, a lesser peak pressure will be developed due to the lesser piston velocity at the time of closure. Prior art systems of the type shown in FIG. 2a did not include the further check valve SV, and its presence should be ignored for the moment.

As the piston begins to close off port IP, the pressure further increases, not only due to the increase in piston linear velocity and increase in flow, (assuming port closure prior to midstroke) but also due to the decrease in unblocked port area irrespective of whether port closure occurs before or after midstroke. The pressure p rises in the cylinder as the port is closed off roughly in accordance with the following characteristic:

$$p = k\omega^2(\cos \omega t)^2 / [A_o - (d/k_1 \omega \cos \omega t)]^2 \quad (2)$$

where A_o is the initial open area of the port, d is the axial width of the port, and k_1 and k are constants. As the port is gradually closed off it becomes an infinite restriction, and hence as the port is closed off the pressure rises exponentially, theoretically toward an infinite value. However, when the pressure reaches a value determined by the spring loading of delivery check valve DV, the valve DV opens and the increase in pressure is thereafter limited. The rate at which the pressure rises as the port is closed off depends not only upon the geometry of the port, but also upon the piston speed. The increase in piston speed not only increases the pressure due to provision of increased flow, but also increases the rate of pressure increase by more quickly closing off the port, so that the rate of pressure increase varies as a fairly high power of pump drive speed. The precise slope of the pressure characteristic will also depend, of course, upon the shape of the inlet port as well as its general width, and the shape of the piston edge which passes over the port to block the port. As the piston is rotated to decrease the delivery per stroke at a given pump drive speed, so that the piston has a greater velocity when it closes off the port, the rate of pressure increase will be seen to increase. Since maximum linear piston velocity occurs at midstroke, the maximum peak pressure for any given pump drive speed will occur when the port is closed off approximately at midstroke, when the pump is adjusted to pump approximately one-half its maximum delivery per stroke.

The rapid increase in pressure as the port is closed off applies a sudden force to the body of valve DV, accelerating it rightwardly against the force of the valve spring and providing a damped oscillation of the valve body. The mass of the valve body, the valve spring, and the viscous resistance of the fuel to motion of the valve body after the valve is opened will be seen to provide a mass-spring-damper second order system. The valve body, eventually returns to a steady-state position such

that cylinder pressure balances the valve spring loading, and cylinder pressure remains substantially at the value determined by the delivery valve spring loading for the remainder of the rightward pumping stroke. The motion of the check valve body required to allow maximum flow through the check valve is assumed to be small compared to the length of the check valve spring, and hence the spring may be assumed to apply a substantially constant force to the check valve body. Because the pressure drops quickly when the delivery check valve opens, the force applied to the valve body has the nature of a brief impulse, the amplitude of which varies as an exponential function of pump drive speed. Thus increased pump drive speed increases the amount which the valve body overshoots. After the overshoot, the check valve maintains cylinder pressure substantially at a value determined by the check valve spring loading. The pressure in the cylinder may increase slightly up to midstroke as piston velocity increases and thereafter decrease somewhat as piston velocity decreases during the latter half of the rightward pumping stroke but no further sudden increase in pressure will occur during the pumping stroke. As mentioned above, the foregoing description of operation assumes that check valve SV is not present.

In accordance with the present invention, pump delivery per stroke may be decreased with increasing pump drive speed from its otherwise value by provision of the further secondary control check valve SV, which is responsive to pump cylinder pressure and operative to spill back increasing amounts of fuel to the supply as pump drive speed increases. The ratio between the mass of the body of a check valve to the spring force of the spring of the check valve may be termed the check valve "time constant". Check valve SV is provided with a smaller time constant than that of delivery check valve DV. As the closure of inlet port IP causes the rapid increase in cylinder pressure, the pressure is applied simultaneously to both the delivery check valve and check valve SV. The pressure temporarily rises above the steady-state delivery valve pressure setting due to the greater inertia or longer time constant of the delivery check valve, which delays its opening. During that temporary high pressure condition the secondary control check valve SV opens, due to its lesser mass, despite its greater spring loading, and opening of valve SV spills back fluid to the supply tank and limits the pressure developed in the cylinder. The amount which valve SV opens will be seen also to depend upon the peak pressure developed in the cylinder, and hence upon pump drive speed. As well as spilling back some fluid, the quick opening of pressure-sensitive valve SV also decreases the time width of the pressure impulse applied to delivery check valve DV, thereby decreasing the overshoot of valve DV.

The variation in volumetric efficiency, or air aspirated per stroke, with speed is ordinarily non-linear for most engines. Also, the variation of peak pump cylinder pressure with pump speed is non-linear, and the variation in the amount of fuel which a typical spring-loaded check valve will pass with a given pressure impulse applied to it is also non-linear. Furthermore, the peak pump cylinder pressure occurring at a given engine speed or pump drive speed varies in accordance with fuel delivery setting, as described above. Because of these varying relationships, it is sometimes difficult to provide a desired fuel-air ratio characteristic over

widely-varying load conditions if a fixed spring loading is used on the check valve SV. In accordance with a further feature of the invention, the loading on the secondary control check valve SV may be varied as a function of the primary control delivery setting, and in FIG. 5 a cam C rotated by the primary control A is effective to vary the spring load on check valve SV.

If the piston in FIG. 2a is rotated to decrease fuel delivery by closing off the inlet port later during the first 10 half of the stroke, the piston will have a greater velocity as it closes off the port, thereby increasing the slope of the pressure characteristic, as will be apparent from expression (2), and thereby providing greater impulses to open the secondary check valve SV. Piston velocity decreases during the latter half of the pumping stroke. Thus maximum peak pressure for a given engine speed is developed if the inlet port is closed approximately at midstroke, which results when the pump is operating at roughly one-half of its capacity. Most engine systems 15 require fuel delivery which varies from none or some small amount up to a maximum required for normal running, although even greater delivery may be required for starting. Since minimum delivery requires inlet port closure very late in the stroke, a pump of the 20 type shown in FIG. 2a when used in such an engine system ordinarily will operate over a range which varies from a minimum delivery condition involving port closure very near the end of the rightward stroke when piston velocity is low, up to a maximum delivery condition 25 involving port closure much earlier during the stroke when piston velocity is greater. If the maximum fuel required by the engine during running conditions is no more than half the maximum pump capacity, it will be seen that the peak pump cylinder pressure developed 30 at a given engine and pump speed will vary directly, though not linearly, with the fuel delivery setting over the entire running range of the engine. Under such conditions, cam C will ordinarily provide a spring-loading 35 to valve SV which generally increases as the delivery is increased. If the engine requires more fuel delivery than half the pump capacity so that inlet port closure must occur prior to midstroke, a plot of the peak pump pressure developed at a given engine speed versus 40 pump delivery will be seen to slope downwardly at the highest delivery values. Under such an arrangement, cam C will ordinarily provide spring-loading which increases as delivery is increased up to a given delivery value, after which cam C will provide decreasing spring-loading as delivery is further increased.

FIG. 2b diagrammatically illustrates a different form of reciprocating variable-delivery constant stroke-length injection pump in which delivery is varied by varying the time during the stroke at which forward pumping is terminated, rather than varying the time at which it begins. The pistons P and AP are reciprocated by the engine with some approximation of simple harmonic motion. As piston P travels rightwardly on a pumping stroke, delivery commences substantially immediately through delivery check valve DV, and continues throughout the rightward pumping stroke until port TP of auxiliary piston AP registers with port SP of collar CO, at which time fuel is spilled back through hose H to the supply tank. The delivery check valve feeds a nozzle extending into the engine air intake structure in the same manner as in FIG. 2a. The piston P contains a bore and a conduit communicating with port TP of auxiliary piston AP. Collar CO is arranged

to be axially adjustable relative to auxiliary piston AP by means of the engine primary control, so that the time or position during the stroke at which forward pumping ceases may be varied to vary the quantity of fuel delivered. Inlet check valve IV admits fuel to the pump cylinder during the leftward return or suction stroke.

First consider the operation without the use of secondary control check valve SV. At the beginning of a rightward pumping stroke, piston speed begins at zero and increases cosinusoidally. Pressure builds up in the pump cylinder substantially immediately to a value greater than the steady-state spring loading of the delivery check valve, and then decreases to a value commensurate with the delivery check valve loading, as the delivery check valve DV opens. While the velocity of the piston P is minimum (zero) at the beginning of the stroke, the acceleration of the piston is then at its maximum value, and assuming simple harmonic motion: $a = s/2 \omega^2 \sin \omega t$. The maximum acceleration of piston P applies a maximum impulse to delivery check valve DV, and the magnitude of the impulse will be seen to vary as the square of engine and pump speed. As the delivery check valve opens, the pressure in the cylinder drops markedly. The pressure then increases somewhat until midstroke (assuming collar CO is adjusted to provide delivery past midstroke) due to the increasing velocity of the piston and increased flow through valve DV, but the pressure does not ordinarily approach the initial peak pressure. When port TP reaches port SP the pressure drops suddenly and delivery valve DV closes. Inasmuch as the peak pressure occurs at the beginning of the stroke, irrespective of the adjustment of collar CO, it will be seen that variation of the delivery setting of collar CO by the engine primary or torque control has no effect on the peak pressure developed within the cylinder.

In accordance with the invention, secondary control check valve SV is provided in FIG. 2b, again with a smaller time constant than delivery valve DV, so that valve SV opens briefly during the pressure peak to spill back fuel to the supply, and it will be apparent that increasing engine speed causes greater impulses to valve SV, thereby spilling back more fuel. Because the magnitude of the pressure peaks does not tend to vary with the delivery setting, it is in general less necessary to use a cam to vary the spring loading on valve SV in FIG. 2b. However, the use of such a cam, in the same manner as in FIG. 2a, allows one to more easily tailor the secondary control valve spill-back amount to a given volumetric efficiency versus speed characteristic, and the use of such a cam with the pump of FIG. 2b is within the scope of the invention.

While FIG. 2b illustrates a reciprocating variable-delivery pump using a constant stroke length, its peak pressure characteristic is essentially the same as that of a number of reciprocating variable-delivery pumps in which the amount of fuel pumped per stroke is varied by varying the pump stroke length. In such pumps, the peak pressure ordinarily occurs at or near the beginning of the stroke, and the magnitude of the peak pressure does not vary appreciably with the fuel delivery or stroke length adjustment. It will be apparent that a secondary control check valve may be connected to the chamber of such a pump in the same manner as with the pump of FIG. 2b, with the check valve spring load-

ing being either varied or not varied as a function of the primary control or stroke length setting.

FIG. 2c diagrammatically illustrates a third form of reciprocating variable delivery, constant stroke-length injection pump of a type shown in greater detail in FIG. 1 and also described in detail in my prior application Ser. No. 786,233. Piston P is reciprocated by the engine with some approximation of simple harmonic motion. A passageway within piston P communicates with the pump chamber and selectively communicates with inlet port IP and outlet port OP. The passageway edge positions vary angularly about the piston so that rotation of the piston varies the time during a given stroke at which inlet port IP is closed off and the time at which outlet port OP is opened, thereby varying the amount of fluid pumped during a rightward pumping stroke. The engine primary control rotatably adjusts piston P to vary pump delivery rate. At the leftward position of the piston inlet port IP is fully opened, and at the rightward end of the pumping stroke outlet port OP is fully opened. The passageway geometry is arranged relative to the two ports so that outlet port OP always opens slightly before inlet port IP is completely closed off at any angular position of the piston. With inlet port IP closing as outlet port OP is opening, the maximum restriction to flow from the pump cylinder occurs during the overlap condition when both ports are slightly open.

Consider initially the operation of the pump of FIG. 2c without secondary control check valve SV. As the piston begins a rightward pumping stroke, fluid is expelled through fully open inlet port IP, and the pressure within the pump cylinder remains low. As the inlet port begins to close off and the maximum flow restriction condition is approached, the pressure in the pump cylinder increases very rapidly, and then as the maximum restriction overlap condition is passed and outlet port OP is opened wider, the pressure decreases. The magnitude of the peak pressure developed in the cylinder will be seen to depend upon both engine speed, which determines the flow rate out of the pump cylinder, and upon the minimum total open area of the two ports when both are slightly open. As the piston is rotated to vary the delivery, it will be seen that the time during the stroke at which the maximum restriction condition occurs will vary, and if the same maximum restriction condition occurs at different piston velocities, which provide different flow rates from the cylinder, it may be seen that the peak pressure obtained will also vary with the engine primary control setting. If the same maximum restriction condition, i.e., same minimum open area during overlap, is made to occur for all delivery settings, the peak pressure at a given pump drive speed will be seen to be obtained if the maximum restriction condition occurs substantially at midstroke, when piston linear velocity is greatest, so that the peak pressure for a given drive speed will occur when the pump is adjusted to pump approximately one-half of its maximum delivery per stroke.

In accordance with the invention, secondary control check valve SV is connected from the pump cylinder to spill fuel during the occurrence of the pressure peaks. One advantage of the pump of FIG. 2c over those of FIGS. 2a and 2b is that the delivery check valve DV may be very lightly loaded, since delivery cannot begin until output port OP is opened, irrespective of pump speed and delivery setting. Furthermore,

while the peak pressure impulse developed in the pumps of FIGS. 2a and 2b and applied to their secondary control check valves is limited by the opening of their delivery check valves, the peak pressure developed in the pump of FIG. 2c is substantially independent of the delivery check valve loading, and thus the secondary control check valve used in the arrangement of FIG. 2c need not have a shorter time constant than that of the delivery check valve or otherwise be adjusted relative to any other check valve.

The above description of FIG. 2c assumes that the same maximum restriction condition occurs during the overlap condition at all angular adjustments of the piston. By suitably shaping and/or slanting the edges of the ports relative to the piston passageway edges one can cause the area of the maximum restriction to vary as the piston is rotated to provide different delivery rates, and hence one can make the amplitude of pressure peaks occurring in the pump of FIG. 2c either more a function of, or less a function of, the delivery setting in whatever manner one chooses. If the minimum port area occurring during overlap is caused to increase somewhat with delivery setting up to one-half of pump capacity, thereby decreasing the maximum restriction with an increased delivery setting up to one-half pump capacity, (and thereafter to decrease with increased delivery if more than one-half pump capacity is used) the magnitude of the pressure impulses will tend to vary less with delivery setting. If the minimum port area during overlap is caused to vary roughly as a sine-squared function with the delivery setting, it will be seen that the magnitude of the pressure peaks occurring at a given engine speed can be made theoretically independent of the delivery setting, so that no variation in check valve spring loading with delivery setting is necessary. Because the pump of FIG. 2a requires that the inlet port be fully closed, providing an infinite restriction at all delivery settings, the magnitude of the pressure impulses occurring in such a pump varies markedly in accordance with the delivery setting, since the delivery setting determines the time during the stroke, and hence the piston velocity at the time the restriction is imposed. The pump of FIG. 2c (and FIG. 1), by not providing an infinite restriction, but instead a controllable partial restriction, the minimum area of which can be made to vary with delivery setting, therefore has the marked advantage that the magnitude of the pressure impulses occurring at a given engine speed may be arranged to vary with delivery setting in accordance with any desired function, or if desired, arranged not to vary appreciably at all.

It has been shown that while the peak pressure developed during a pumping stroke at a given engine speed varies with primary control setting with the pump of FIG. 2a, with maximum pressure being developed when this pump is pumping at roughly one-half its maximum capacity, that the peak pressure developed in the pump of FIG. 2b tends to be largely independent of the primary control setting, and that the peak pressure developed at a given engine speed in the pump of FIG. 2c may or may not vary appreciably with delivery setting, depending upon whether its port geometry is arranged to provide a minimum restriction area which varies with delivery setting. The amount of fuel spilled back by the secondary control check valve of any of the three systems of FIGS. 2a, 2b and 2c varies with the peak pressure impulse applied to the check valve in a

manner dependent upon the check valve passage geometry, as well as upon its inertia and spring loading.

FIG. 1 illustrates in a cross-section view a form of injector pump disclosed and described in detail in my abovementioned Application Ser. No. 786,233, with certain modifications made thereto in accordance with the present invention. The pump is of the basic type described above in connection with FIG. 2c, but shown adapted for two-cycle engine use to pump oil as well as fuel. The pump comprises a generally-cylindrical central casting 120 having a rear head 121 and a front head 122 bolted thereto by means of bolts (not shown), with a suitable gasket (not shown) preferably provided between each head and the central casting. Shaft 123 rotated by the engine crankshaft carries eccentric cam 127. Rotation of cam 127 reciprocates tappet 81, which is carried in bushing 82 with an O-ring seal 83a. The right end of tappet 81 bears against the left end of piston 130, which reciprocates within sleeve 129a. A spring 133, only a portion of which is shown, is inserted between head 122 and a right-end face of piston 130 and operates to return piston 130. A lower gear sector 83 pinned to piston 130 is engaged by upper gear sector 84 pinned to control shaft 131, so that rotation of shaft 131 angularly positions piston 130. Shaft 131 is angularly positioned by accelerator pedal or throttle control 103 via arm 104 and a suitable mechanical linkage shown merely as a dashed line. Upper gear sector 84 is axially wider than lower gear sector 83 so that the gear sectors remain enmeshed as sector 83 reciprocates with piston 130.

Oil is supplied from an oil supply tank (not shown) to chamber 128 via a check valve (not shown) and a pipe connection made at 128a on the side of central casting 120. Fuel is supplied to chamber 164 from fuel tank 146 via conduit 145c. Oil and fuel inlet ports are provided in sleeve 129a at 134 and 136, respectively, and oil and fuel outlet ports are provided at 135 and 137. Oil piston 161 is urged rightwardly against front head 122 by inner coil spring 162. Holes drilled in main casting 120 at 142a and 147a connect the outlet ports with longitudinally-extending passages in which check valves 150 and 151 are located, and plugs 142c, 147c close the ends of passages 142 and 147a. Check valves 150 and 151 at the outlet side of the injector pump each communicate with mixing chamber 143 provided in front head 122. Two V-shaped grooves are milled across the outer periphery of piston 30 as shown by dashed lines at 138 and 139. The bottom of V-groove 138 communicates with oil chamber 155 inside piston 130, and the bottom of V-groove 139 communicates with fuel chamber 160 situated to the right of piston 130 and partially within piston 130. At various axial positions of piston 130 V-groove 138 connects chamber 155 to only chamber 128 via oil inlet port 134, or to both inlet chamber 128 via inlet port 134 and to mixing chamber 143 via outlet port 135 and check valve 150, or to only mixing chamber 143 via outlet port 135 and check valve 150. At corresponding axial positions of piston 130, V-groove 139 connects fuel chamber 160 to only chamber 164 via inlet port 136, or to both chamber 164 via inlet port 136 and mixing chamber 143 via outlet port 137 and check valve 151, or to only mixing chamber 143 via outlet port 137 and check valve 151. Inlet ports 134 and 136 and outlet ports 135 and 137 each comprise an opening which extends par-

tially around sleeve 129a, with each such slot having a uniform dimension measured in the axial direction of sleeve 129a.

The cutting of V-shaped grooves on the periphery of cylindrical piston 130 gives the grooves a width which varies with the angular position of the groove around the piston. As is described in greater detail in my mentioned prior application Ser. No. 786,233, varying the angular position of the piston within sleeve 129a by means of control shaft 131 varies the time during a given piston stroke at which the V-grooves will communicate with the outlet ports and the time at which the V-grooves will be cutoff from the inlet ports, and hence determines the amount of fuel and oil which the pump will pass to the mixing chamber during the piston stroke.

Piston 130 is shown at its leftmost position in FIG. 1. As piston 130 is urged rightwardly on a pumping stroke, at the beginning of the stroke V-groove 138 connects oil piston chamber 155 via inlet port 134 to chamber 128 so that oil within chamber 155 is expelled from chamber 155 back into chamber 128, and V-groove 139 connects fuel chamber 160 via inlet port 136 to fuel chamber 164, so that fuel is expelled from chamber 160 back into chamber 164. At an intermediate time during the stroke determined by the angular position of piston 130, the V-grooves first reach and unblock outlet ports 135 and 137 and then move out of communication with and block inlet ports 134 and 136. Provision of such an overlap condition with the outlet ports always slightly opening before the inlet ports are fully closed prevents damage due to fluid blockage. Thereafter during the rightward pumping stroke, as the inlet ports fully close and the outlet ports increasingly open, oil is expelled from chamber 155 via outlet port 135, and fuel is expelled from fuel chamber 160 via outlet port 137, and the fuel and oil mix in mixing chamber 143. The mixing chamber connects to a nozzle (not shown) which injects the fuel-oil mixture into the engine air intake duct. As mentioned in my prior application, the fuel and oil are not mixed in a mixing chamber in some applications, and instead, only the fuel is piped to the nozzle and the oil is pumped to various oil holes at desired lubrication points within the engine.

The basic pump of FIG. 1 and FIG. 2c differs markedly from many somewhat similar prior art fuel metering pumps in that an inlet port is closed and a separate outlet port is opened during a pumping stroke, while the prior art generally has left each pump chamber in constant communication with an outlet check valve during the entire pumping stroke, so that forward pumping past a prior art check valve occurs either immediately (as in FIG. 2b) or as soon as an inlet port is closed off to prevent return pumping (as in FIG. 2a). If the fluid supply has positive pressure, the check valve in such prior systems must be loaded to at least the same pressure in order to prevent forward pumping prior to complete closure of the inlet port. And even if the fluid supply is not pressurized, the pressure in the prior art pump chambers necessarily builds up prior to complete closure of their inlet ports, in amounts dependent upon pump speed and dependent upon the amount of restriction to return flow between the pump chamber and the fluid supply, with the amount of said restriction increasing from a basic amount to complete blockage as the inlet port is gradually closed off. If for-

ward pumping is not to occur prior to complete closure of the inlet port, the check valve in the prior systems must be loaded to the highest such pressure which may occur prior to inlet port closure. The heavier check valve loading necessarily results in higher pressures in the pump chamber, thereby requiring a more precise piston-cylinder fit. In the pump of FIGS. 1 and 2c, forward pumping cannot occur prior to opening of an outlet port, irrespective of whether the supply is pressurized, and hence the instant at which forward pumping begins during a pumping stroke remains substantially independent of pump speed and outlet check valve loading, making the quantity of fluid delivered per stroke similarly independent of pump speed and check valve setting.

In accordance with the embodiment of the present invention illustrated in FIG. 1, fuel chamber 160 is connected to fuel inlet chamber 164 via a spring-loaded check valve 163, the spring loading of which is shown made variable as a function of control shaft 131 position, by means of cam 131a carried on control shaft 131. Rotation of control shaft 131, as by means of accelerator pedal 103 and arm 104, so as to rotate piston 130 to increase oil and fuel flow rates causes cam 131a to vary the spring loading on check valve 163. The precise shape of cam 131a will depend upon the desired variation of fuel-air ratio, the variation in air flow with engine speed due to the engine air intake structure, the variation of pump cylinder peak pressure with engine speed, the variation of pump cylinder pressure with delivery setting, and the variation in the amount of fuel spilled back through check valve 163 with peak pressure, all of which determine the variation in the amount of fuel spilled back for a given engine speed with a given primary control delivery setting. In some embodiments of the invention, the spring loading of check valve 163 need not be varied as a function of throttle position. In those embodiments cam 131a may be eliminated and check valve 163 held in position with a fixed spring loading by a plug in head 122. The passageway which includes a check valve 163 extends generally in a direction so as to intersect shaft 131 if cam 131a is used. If no cam is used it will be apparent that the passageway may extend out radially in another direction, such as perpendicularly to the plane of FIG. 1.

In the pump of FIG. 1 the inlet and outlet ports are spaced relative to their respective V-grooves so that maximum restriction to flow from each V-groove occurs during the intermediate or overlap interval when each V-groove slightly communicates with both its inlet port and its outlet port. Therefore, the maximum pressure which occurs in pump cylinder 160 during a pumping stroke occurs during that intermediate or overlap interval when both inlet port 136 and outlet port 137 are both only slightly open, so that maximum restriction to flow from chamber 160 is provided, and the magnitude of the maximum pressure will be seen to vary with pump piston speed. The pressure in chamber 160 will be seen to drop from its maximum value as piston 130 thereafter continues to travel rightwardly and outlet port 137 is increasingly unblocked.

As was explained above in connection with FIG. 2c, the maximum peak pressure developed in the pump cylinder for any given engine speed tends to occur if the maximum restriction condition when both inlet and outlet ports are slightly open occurs when the piston has maximum linear velocity. Maximum piston velocity

usually occurs somewhere near midstroke if an approximation of simple harmonic motion is used to reciprocate the piston, and adjustment of the pump to cause the two ports to overlap around the midstroke causes the pump to operate at approximately one-half its maximum capacity. If one-half or less of the pump maximum capacity is sufficient to supply the maximum fuel requirements of the engine, the overlap will occur during the last half of the pumping stroke, and if the shape and spacing of ports 136 and 137 and V-groove 139 provide the same minimum area restriction as piston 130 is rotated to give different delivery rates, increasing the primary control setting to call for increased delivery will increase the peak pressure developed for a given engine speed and tend to increase the amount of fuel spilled back by the secondary control check valve 163, and in such an arrangement cam 163 may be shaped to provide an increase in check valve spring loading as the primary control setting is adjusted to provide greater fuel flow. If, on the other hand, the maximum fuel requirements of the engine require more than one-half pump capacity, so that forward pumping is sometimes required during the first half of the stroke, and the port and V-groove geometry again provides the same minimum area restriction at different angular positions of piston 130, the cam may be shaped to increase check valve spring loading until the primary control is adjusted to the midstroke overlap condition, and thereafter to decrease the spring loading as greater amounts of fuel are called for. However, if rotation of piston 130 is arranged to vary the minimum area of the maximum restriction which occurs during the overlap condition, the maximum pressure developed in cylinder 160 can be made to vary directly with delivery setting, or not to vary appreciably with delivery setting, or even to vary inversely with delivery setting, if desired. If the maximum pressure does not vary appreciably with delivery setting, it will be apparent that variation of the spring loading on check valve 163 becomes unnecessary.

FIG. 1b contains three unrolled or developed views illustrating the geometry of V-groove 139 relative to ports 136 and 137. Angular adjustment of piston 130 to provide different delivery rates amounts to vertical displacement of the V-groove in FIG. 1b relative to the ports. On each pumping stroke V-groove 139 moves rightwardly relative to the ports from a beginning position in which the V-groove is centered on the inlet port 136. V-groove 139 is shown at I in a minimum delivery position at the time during the overlap condition when it least registers with inlet port 136 and outlet port 137, at II in a medium delivery position at the time during the overlap condition when it least registers with the ports, and at III in a maximum delivery position at the time when it least registers with the ports. It will be seen that the minimum overlap area varies from a small area in I, to a larger area in II, and then to a smaller area at III. Times t_1 , t_2 and t_3 indicate the times after the beginning of the pumping stroke at which the maximum restriction occurs under the three different delivery conditions. Thus it will be seen that the amount of maximum restriction varies from a minimum at low delivery rates up to a maximum at approximately one-half capacity, down to a minimum at maximum delivery. Since piston speed at the time of the overlap condition varies in approximately the same manner, it will be apparent that the variation in restriction may be used to offset

the variation in piston speed at the time of overlap, so that the magnitude of the pressure impulses developed at a given engine speed and pump drive speed tends to be largely independent of the pump delivery setting.

- 5 If cam 131a is eliminated and a constant spring load is used on check valve 163, and if the port geometry provides the same minimum restriction at different delivery settings, the amount of fuel spilled back through the check valve at a given engine and pump speed will 10 increase with the primary control delivery setting as the primary control is varied from minimum flow to one-half pump capacity, thereby leaning out the fuel-air ratio, and as the primary control delivery setting is further advanced at the same engine speed to provide 15 greater flow than one-half pump capacity, the amount of fuel spilled back through the check valve will decrease, thereby providing an increasingly-enriched mixture at increasing delivery settings.

In the arrangement shown in FIG. 1, wherein increasing fuel spillback occurs at increasing engine speeds due to light load conditions but no comparable oil spillback occurs it will be seen that the amount of oil pumped per stroke remains substantially constant, thereby providing larger oil-to-fuel and oil-to-air ratios 20 during higher speed-lighter load conditions. Such operation is wholly satisfactory for many two-cycle engine applications, and particularly in those two-cycle engine applications where the oil is not mixed with the fuel but instead pumped to various lubrication joints within the engine.

If desired, the oil-to-fuel and oil-to-air ratios may be tailored by providing a secondary control oil check valve in similar fashion to spill back oil in amounts varying with engine speed.

25 30 35 While FIG. 1 illustrates a system which dispenses metered amounts of oil as well as fuel, such as is used with two-cycle engine systems, it is important to recognize that the invention is in no way restricted to fuel injection systems which dispense two fluids, and is quite as applicable to four-cycle engine systems wherein oil is not injected into the engine.

40 45 50 55 60 65 While the mixing and metering pump of FIG. 1 uses separate oil and fuel pistons (161 and 130) to pump oil and fuel with a desired ratio, an alternative embodiment shown in FIG. 1a dispenses with the need for a separate oil piston, and the need for V-groove 138 on piston 130 and the need for oil inlet and outlet ports 134 and 135 in sleeve 129a. In FIG. 1a oil is supplied to oil chamber 128 via an inlet conduit 128a which carries duckbill check valve 601. As cam 127 moves fuel piston 130 on a rightward fuel-pumping stroke, thereby increasing the volume of chamber 128, oil is drawn into chamber 128 through check valve 601. As spring 133 moves piston 130 leftwardly, thereby decreasing the volume of chamber 128, oil is expelled past oil outlet check valve 150 to mixing chamber 143. The amount of oil which is drawn into chamber 128 during a rightward stroke and dispensed to the mixing chamber on the piston return stroke depends upon the cross-sectional area of piston 130 times the length of the piston stroke, less the cross-sectional area of tappet 81 times the same stroke length, since tappet 81 increasingly enters chamber 128 from bushing 82 as piston 130 increasingly leaves chamber 128. If tappet 81 is very slightly less in diameter than piston 130, very little oil will be pumped compared to the amount of fuel pumped. It will be seen that a constant amount of oil

will be pumped per stroke, irrespective of the adjustment of control shaft 131. In a variety of systems, and in particular those which drive constant loads, it is considered unnecessary to maintain a constant fuel-oil mixture ratio. The pump in FIG. 1a is shown without the cam 131a and check valve 163 utilized in FIG. 1 to provide secondary control, and such a feature obviously can be added to FIG. 1a, if desired.

It will become immediately apparent to those skilled in the art that the main principles of the invention are readily applicable to systems using variable stroke length pumps, for example, as well as the specific pump types shown. A variety of modifications will occur to those skilled in the art. Various of the check valves shown as needle valves may comprise ball or poppet-type valves instead, for example.

It will thus be seen that the objects set forth above, among those made apparent from the preceding description, are efficiently attained, and since certain changes may be made in the above constructions without departing from the scope of the invention, it is intended that all matter contained in the above description or shown in the accompanying drawings shall be interpreted as illustrative and not in a limiting sense.

The embodiments of the invention in which an exclusive property or privilege is claimed are defined as follows:

1. A fluid pump, comprising, in combination: means defining a pump chamber having first and second ports; means for supplying fluid to said chamber; means for cyclically opening and closing said ports to provide three distinct conditions including a first condition in which said chamber communicates solely with said first port, a second condition in which said chamber communicates decreasingly with said first port and increasingly with said second port, and a third condition in which said chamber communicates solely with said second port, said ports being arranged so that the port area communicating with said chamber reaches a minimum finite amount during said second condition and the pressure in said chamber reaches a maximum during said second condition; and check valve means connected to release fluid from said chamber when said pressure exceeds a predetermined value, said means defining said pump chamber comprising a cylinder having first and second ports and said means for cyclically opening and closing said ports comprises a piston adapted to reciprocate within said cylinder.

2. A pump according to claim 1 in which said piston is adapted to reciprocate through fixed-length forward and return strokes within said cylinder and includes an edge which varies in axial position angularly around a portion of said piston so that rotation of said piston within said cylinder varies the times during a forward stroke at which said ports are opened and closed.

3. A pump according to claim 1 in which said piston is adapted to reciprocate through fixed-length forward and return strokes within said cylinder and is rotatably adjustable to vary the amount of fluid pumped per stroke through one of said ports by varying the point during a stroke at which said one of said ports is opened, and in which said piston is shaped so that rotation of said piston varies the minimum port area reached during said condition.

4. A reciprocating pump, comprising, in combination: a cylinder; piston means adapted to reciprocate within said cylinder; drive means for reciprocating said

piston at a velocity which varies over the stroke of the piston at a given speed of said drive means, said cylinder having an inlet port and an outlet port, said piston means being operable to increasingly open said outlet port and increasingly close said inlet port during a portion of said stroke and thereby pass through a maximum restriction condition in which a minimum total area of both ports is open, said piston means being adjustable to control the amount of fluid expelled from said outlet port during said stroke by controlling the points during said stroke at which said piston means opens said outlet port and closes said inlet port, said piston means and said ports being shaped and spaced so that adjustment of said piston to control the amount of fluid expelled varies the minimum open port area occurring during said maximum restriction condition, thereby varying the maximum pressure which occurs in said cylinder during said stroke.

5. A pump according to claim 4 having pressure-sensitive valve means operable when the pressure in said cylinder exceeds a predetermined value to divert fluid from said cylinder and thereby further control the amount of fluid expelled from said outlet port during said stroke.

6. A pump according to claim 4 in which said piston includes an edge which varies in axial position angularly around a portion of said piston so that rotation of said piston within said cylinder controls said points during a stroke at which said piston opens said outlet port and closes said inlet port.

7. A pump according to claim 4 wherein said drive means reciprocates said piston with an approximation of simple harmonic motion.

8. A pump according to claim 4 in which adjustment of said piston to increase the amount of fluid expelled from said outlet port increases said minimum open port area occurring during said maximum restriction condition.

9. A pump according to claim 4 in which adjustment of said piston to increase the amount of fluid expelled from said outlet port decreases said minimum open port area occurring during said maximum restriction condition.

10. A pump according to claim 4 wherein said drive means reciprocates said piston at a velocity which varies substantially sinusoidally over the stroke of said piston.

11. A pump according to claim 4 in which adjustment of said piston means to vary the amount of fluid expelled from said outlet port varies said minimum open port area occurring during said maximum restriction condition in relation to the velocity of said piston when said maximum restriction condition occurs, so that said maximum pressure is substantially independent of said adjustment of said piston means.

12. A pump according to claim 4 in which adjustment of said piston means to vary the amount of fluid expelled from said outlet port varies said minimum open port area occurring during said maximum restriction condition in accordance with a function of the position during a stroke at which said maximum restriction condition occurs, so that the said maximum pressure occurring in said cylinder during said maximum restriction condition varies substantially as a function of said given speed of said drive means and does not vary substantially with said adjustment of said piston means.

13. A pump according to claim 4 in which adjustment of said piston to vary the amount of fluid expelled from said outlet port varies said minimum total open port area occurring during said maximum restriction condition, from a finite first amount of minimum total open port area at a first delivery condition in which a first amount of fluid is expelled from said outlet port during each said stroke to a second amount of minimum total open port area at a second delivery condition in which a second amount of fluid is expelled from said outlet port during each said stroke.

14. A pump according to claim 13 in which said second amount of fluid exceeds said first amount of fluid and said second amount of minimum total open port area exceeds said first amount of minimum total open port area.

15. A pump according to claim 4 in which adjustment of said piston to vary the amount of fluid expelled from said outlet port varies said minimum total open port area occurring during said maximum restriction condition from said second amount of minimum total open port area at said second delivery condition to a third amount of minimum total open port area at a third de-

livery condition in which a third amount of fluid is expelled from said outlet port during each said stroke.

16. A pump according to claim 13 in which said second amount of fluid exceeds said first amount of fluid and said first amount of minimum total open port area exceeds said second amount of minimum total open port area.

17. A pump according to claim 15 in which said second amount of fluid exceeds said first amount of fluid and said third amount of fluid exceeds said second amount of fluid, and said second amount of minimum total open port area exceeds both said first amount of minimum total open port area and said third amount of minimum total open port area.

18. A pump according to claim 15 in which said second amount of fluid exceeds said first amount of fluid and said third amount of fluid exceeds said second amount of fluid, and said second amount of minimum total open port area is less than said first amount of minimum total open port area and said third amount of minimum total open port area.
